UNITED STATES PATENT OFFICE.

DAVID L. LINDQUIST, OF YONKERS, NEW YORK, ASSIGNOR TO OTIS ELEVATOR COMPANY, OF JERSEY CITY, NEW JERSEY, A CORPORATION OF NEW JERSEY.

TRACTION-ELEVATOR SYSTEM.

1,047,255.

Specification of Letters Patent. Patented Dec. 17, 1912.

Application filed July 1, 1908. Serial No. 441,393.

To all whom it may concern:

Be it known that I, DAVID L. LINDQUIST, a subject of the King of Sweden, residing at Yonkers, in the county of Westchester and State of New York, have invented a new and useful Improvement in Traction-Elevator Systems, of which the following is a specification.

My invention relates to motor controlling apparatus, particularly that used for traction elevators or frictional driving apparatus, although it may have a general application.

One of the objects of my invention is the provision of improved and efficient apparatus for controlling electric motors.

More particularly it is the object of the present invention to provide simple and efficient controlling apparatus for electric motors when operating comparatively heavy loads, as, for example, an elevator car in which a safe is being hoisted.

The specific objects of the invention will appear hereinafter, the novel combinations of elements being set forth in the appended claims.

In the accompanying drawings, Figure 1 represents a traction elevator to which my invention may be applied; Fig. 1^a is a fragmentary view of driving gear mechanism for the traction sheaves; Fig. 2 represents a wiring diagram of a system of control including my invention; Fig. 3 represents auxiliary brake apparatus which is used when heavy loads are lifted; and Fig. 4 is a sectional view of a magnetic driving sheave.

Referring to Fig. 1, C designates an elevator car which may be suitably guided to move up and down in the elevator shaft in the usual way, S designates a controlling switch in the car, and SW a safety switch in the car. 1 are the cables which are secured to the top of the car and extend upwardly over the frictional driving sheave or drum 2, thence downwardly around the direction sheave 3, upwardly over the sheave 2, and finally downwardly to the counterweight W which is associated with the fixed guides 4, 4. In some instances the driving sheave 2 is arranged at the lower end of the elevator shaft instead of at the upper end as shown. Furthermore, the sheave 3 for securing additional friction may be omitted when comparatively light loads are to be lifted, but

when heavy loads like safes are to be lifted 55 the sheave 3 should be included. It should be noted that this sheave 3 is preferably placed at one side so as to act also as a deflection sheave for the cables extending upwardly from the car or those extending 60 downwardly to the counterweight. Arranged in the path of travel of the moving part of the elevator, in this instance the cam 5 carried by the car, are a series of limit switches 6 at the upper limit of travel 65 of the car and a series of additional limit switches 6' at the lower limit of the car travel. The journals of the shafts of the direction sheave 3 are provided with fixed bearings 7, 7 at the upper end of the hatchway or elevator well. Adjacent thereto is the fixed bed-plate 8 for supporting the electric motor M and the standards 9, 9' and 10. The standards 9, 9' are provided with bearings for the shaft 11 to which are 70 connected the driving drum 2 and brake pulley 12; also the extra brake pulley 321. To the standard 10 are pivoted the brake bands 13 which carry the brake shoes arranged to be brought against the pulley 12 80 by the brake springs 14 and released therefrom by the electro-magnet 15. The latter may be supported by a bracket 16 fastened to and extending from the uppermost end of the standard 9. It should be understood 85 that the frictional driving apparatus associated with the power transmitting cables connecting the car and counterweight may be varied in details and arrangement as desired, and other appliances added thereto. 90 This is also true with regard to the brake apparatus and the type of motor. Preferably, however, the motor is of the multi-polar type, with a series-connected armature and a shunt field. One of the appliances which may be added, particularly in the operation of heavy loads, is the gear wheel or wheels 204 meshing or engaging the peripheries of one of the flanges of each of the drums 2, 3. Such gearing may be 100 frictional or spur gearing and connected between the shaft 11 and the countershaft 206 independently of the drums 2 and 3, but rotating therewith, so that the drum 3 will be actuated positively from the shaft 11. 105 In Fig. 1^a is shown one form of mechanism which may be used to move the gear wheel 204 into or out of driving engage-

ment with the drums 2 and 3. As here shown, a rock-shaft 300 which is journaled in the motor frame forms a pivot for the bell-crank lever comprising the long arm 304 and the short arm 301. A link 302, which is adjustable as to length, connects the arm 301 to the gear wheel 204 which is guided to move over a definite path by the fixed guideways 308. At a fixed point 303 10 is pivoted another link comprising the screw-threaded rods 306, 306' and the turnbuckle 307. By operating the turnbuckle in one direction or the other, movement of the gear wheel 204 may be effected to pull 15 the same into engagement with the wheels 2 and 3 or push the same out of engagement therewith. It being more difficult to move the gear wheel 204 into engagement with the wheels 2 and 3, than to withdraw it I have arranged the mechanism so that the 20 link 302 will be put in tension when the turnbuckle is operated to move the rods 306 and 306' toward each other to effect a positive connection between the wheels 2 and 3 through the gear wheel 204. This arrangement is desirable, as the link 302 can better withstand a tensional strain than one of compression.

The driving sheave 2 for the purpose of 30 preventing slipping of the cables when handling heavy loads, is preferably in the form of a magnetic sheave as shown in Fig. 4. The sheave comprises a body portion, consisting of two sections 309 and 310 of 35 magnetic material bolted together, a magnetic coil 311, and a peripheral portion comprising alternate rings 312 and 313 of magnetic and non-magnetic material, respectively. The ends of the magnet coil are 40 connected to the slip rings 314 and 315 through which current is supplied to the coil. This magnetic sheave is not herein claimed, as it is covered by my co-pending application Serial No. 381,020, filed June 27, 45 1907. Although I prefer this type of magnetic sheave, any other type of such sheave may be used if desired, its function being to secure greater adhesion between the driving ropes and the peripheral grooves of the 50 sheave when a heavy load, such as a safe, is being lifted.

The auxiliary brake mechanism shown in Fig. 3 is also used only when heavy loads are to be lifted. The brake levers 316, 316' are 55 pivoted at 317, 317' to a bracket 318 on the bed-plate of the motor. The brake shoes 319, 319' pivoted at 320, 320' to the brake levers are adapted to bear against the periphery of the brake pulley 321 secured to 60 the motor shaft. The brake-applying springs 322, 322' are mounted on a rod 323 which extends loosely through openings in the upper ends of the brake levers. The outer ends of the brake springs bear against 65 collars 324, 324' adjustably mounted and

held in position by the adjusting and locking nuts 325, 325'. The brake magnet comprises a magnetic frame 326, a coil 327, and the cores 328, 328'. The brake shoes are yieldingly held in their normal positions 70 relatively to the brake levers by the adjustable springs 329, 329'. A link 330^a and a bell crank lever 330^b may be used to open and close an electric switch controlling a resistance in series with the brake coil 327. 75 As this switch mechanism forms no part of the present invention it is not herein shown in detail. The arrangement of the switch, resistance and brake coil may be similar to that of the brake coil 15', resistance 123, and switch 26, as shown in Fig. 2. When the elevator is used for carrying passengers or light loads, the auxiliary brake is mechanically held in an off position or in an inoperative condition by means of the nuts 330, 330' 80 threaded onto the rod 323, and which hold the brake levers apart so that the sheave runs freely. By moving these nuts inwardly along the rod 323, the brake levers are left free to be operated by the brake springs. 85 The lock nuts 331, 331' may be used to hold the nuts 330 and 330' in their adjusted positions.

In Fig. 1 is shown also the controller board B of slate or other insulating material for carrying most of the switches, electro-magnets, and the circuits and connections illustrated in Fig. 2. L designates the main line switch controlling the continuity of the main circuit from the source 100 of current supply through the main lines a and b. P designates the potential switch, R, R' the reversing switches, A the accelerating magnet, ALM the auxiliary load magnet, EPSM the excess potential safety 105 magnet, SFSM the shunt field safety magnet, FSM the fast speed magnet, and H the manual switch for changing the connections for light load operation to heavy load operation. 117, 18, 19 and 20, and 21, 22, 23 and 24 are speed controlling switches arranged to be operated by electromagnets.

Similar characters of reference designate corresponding parts throughout the various views.

Referring now to Fig. 2, it will be seen that in addition to the parts already mentioned there are represented a governor switch G for controlling the shunt field resistance SFR and the potential switch P; also a switch 25 which may be associated with safety apparatus carried by the car. The three-pole manual switch H of Fig. 1 is shown diagrammatically in Fig. 2 separated into individual manual switches 208, 120 209; 210 and 211. 212 designates a push button switch, preferably located in the car, to effect the maximum application of the brake independently of the car switch S. 125 15' designates the main brake solenoid, and 130

26 an electric switch operated by movement of the plunger 27. 28 designates the shunt field winding, 29, the motor armature, 30 the main or maximum starting current 5 resistance or safety resistance, 31 the minimum starting current resistance, and 32 the by-pass resistance. 33 and 33' are auxiliary switches associated with the two portions of the reversing switch to control the brake magnet. 34 and 34' designate limit switches which are opened when the car goes beyond its normal limits of travel. When the motor is at rest, I prefer to have the shunt field winding 28 connected in series with the 10 shunt field resistance SFR so that when the main line switch L is closed as indicated, the circuit may be traced from the positive main *a* through the blade 35, conductors 36, 37, 38, shunt field safety magnet SFSM, conductor 20 39, shunt field winding 28, shunt field resistance SFR, conductors 40, 41, switch blade 42 out to the negative main *b*, it being understood of course that the positive and negative mains lead to a source of suitable current supply. The shunt field will therefore be permanently excited, but its strength will vary according to the amount of the resistance SFR and the potential across the mains. The shunt field corresponding to full car speed is left on permanently for the sake of safety, and also to prevent too sudden acceleration with heavy load on down motion of the car or light load on up motion. Connected across the shunt 25 field winding 28 is a high resistance 43 to take up the shunt field discharge in the event that the shunt field circuit should be interrupted. This high resistance is shown variable, for the reason that it may be omitted 30 if desired. Some of the other resistances in Fig. 2 are also shown as variable to indicate their omission in some instances.

The car switch S is preferably like that shown in the patent to Carichoff, No. 45 772,086, granted October 11, 1904, for an improvement in electric elevator apparatus, although any other type of switch may be used if desired, the one herein shown being merely for illustrative purposes. Although 50 any type of motor may be used, dependent upon the use to which the controlling apparatus is put, I prefer to employ in connection with traction elevators a shunt wound motor having a comparatively high armature resistance. The car switch is in this instance shown as comprising a lever 44 pivoted at its lower end to a fixed support in the car and carrying an arc-shaped rack 45 which meshes with the gear 46. The latter 55 is pivoted to the casing of the car switch and is operatively connected to the conducting segments 47 and 48, the former being arranged to move into engagement with the fixed contacts or spring-pressed contacts 49 and 50, and the latter being arranged to en-

gage the fixed contacts or spring-pressed contacts 51, 52, 53, 54, 55, 56, 57, and 51', 52', 53', 54', 55', 56', 57'. It will therefore be seen that when the lever 44 is moved in the direction of the arrow marked "up" the segment 48 will engage the contacts 51 to 57, inclusive, while the segment 47 will engage the contact 49.

Let it be assumed that the main line switch L is closed, as also the potential switch P, and that there is proper potential across the mains for the desired operation of the electric motor; then if the lever 44 is moved for operating the car in an up direction, the segment 48 will first engage the contact 51. A short time afterward the segments 47 and 48 will engage substantially at the same time the contacts 49 and 52, whereupon a circuit will be closed from the positive main *a* through the blade 35, conductor 36, fuse 58, blade 59, conductors 76, 213, magnet 214, resistance 215, conductor 66, contact 51, plate 67, contact 49, conductor 68, normally closed switch 208, switch 25, conductor 69, blade 70 of the safety switch SW, conductor 71, fuse 72, conductor 73, contact 74, blade 75, conductor 41, blade 42 to the negative main *b*. The magnet 214 will thereupon close the switches 216 and 217. A circuit may then be traced from the contact 60, through conductor 61, switch 217, brake resistance 64, switch 26, brake magnet solenoid 15', conductor 218, limit switches 62' and 62, conductors 219, 71, to the contact 74. A circuit is also closed from the positive main through conductors 76, 213, switch 216, conductor 220, limit switch 80, conductor 81, solenoid 83 of the magnet for operating the reversing switch R', conductor 84, limit switch 85, conductor 86, contact 52, plate 67, contact 49, conductor 68, switch 208, switch 25, switch SW, conductor 71, contact 74, and thence out to the negative main. The relative position of the contact 49 of the car switch S is shown such that segment 47 does not engage the same until the segment 48 engages the contact 52, so that the brake apparatus will be released substantially at the same time that the reversing switch is operated to establish the motor circuits in a direction corresponding to the desired direction of the car. When the segment 48 of the car switch engages the contact 52, a circuit is established through the solenoid 83 as just traced. It will now be seen that the brake magnet solenoid 15' is initially placed in series with the resistance 64 in a circuit connected across the mains, and that the solenoid 83 is connected in a circuit across the mains. When the solenoid 83 receives current, it will actuate its core or plunger 87 and thereby lift the contacts 88 and 89 into engagement with the contacts 90 and 91, respectively, and separate the contacts 92 and 93 from the con-

5 contacts 94 and 95. The motor circuit indicated by the heavy lines will now be closed and may be traced from the positive main to conductor 76, and thence through the 10 windings of the blow-out coil 96, contacts 90, 88, conductor 97, contacts 98, 99, conductor 100, minimum starting resistance 31, conductors 101, 102, brush 103 of the motor armature 29, brush 104, conductors 105, 106, 15 coil 107 for holding the plunger 108' in its lowermost position to secure firm connection between the contacts 98, 99 and contacts 108, 109; thence the circuit continues through the latter contacts and by conductor 110 to 20 and through conductor 111, main starting resistance 30, conductor 112 to the blade 75 which is connected to the negative main. From the junction 113 of the conductors 101 and 102 a shunt path extends by conductor 25 114 through a plurality of blow-out coils 115, a series of closed switches 24, 23, 22 and 21, conductor 116, a section or small portion 117 of the by-pass resistance 32, and thence by conductor 118 to the motor armature 29 brush 104. It will now be seen that the 30 starting resistances 31 and 30 are placed in series with the motor armature and that the section or portion 117 of the by-pass resistance 32 is placed in shunt to the motor armature.

35 When the switch R' is closed, the auxiliary switch 33' is also closed, in this instance being connected to operate substantially at the same time. The circuit controlled by the switch 33' is a shunt circuit around the resistance 64 between the contact 221 and the junction 222, and includes the conductors 120 and 223. Therefore, 40 when the reversing switch R' is closed and the auxiliary switch 33' is closed, the resistance 64 will be short-circuited to cause more current to flow through the brake magnet coil 15'. As soon as the brake magnet receives sufficient current to release the 45 brake, the switch 26 is opened and the resistance 123 inserted in series with brake magnet coil 15'. It should be noted that the resistance 64 may be sufficient to prevent the brake from being released when the 50 controlling switch in the car is initially operated, and that not until the reversing switch R' is closed does the brake magnet solenoid 15' receive sufficient current to operate the brake apparatus to released position. After 55 the brake has been released, the resistance 123 is inserted in series with the brake magnet so as to minimize the consumption of current after the brake magnet has done its work, inasmuch as it requires less power 60 for the brake magnet to hold its plunger in its uppermost position and consequently the brake magnet in released position, than to initially lift the said plunger and actuate the brake mechanism connected thereto. It 65 should also be noted that the terminals of

70 the brake magnet circuit are at the contacts 60 and 74 which are isolated with respect to the other contacts of the potential switch P, so that when the latter is opened the 75 brake magnet circuit will be entirely disconnected from both mains and also from the motor. The brake magnet is therefore entirely disconnected when the potential switch is open from any possible source of current which would tend to hold the brake 80 mechanism released, for instance, when the motor acts as a generator. This arrangement insures the application of the mechanical brake to stop the motor shaft and the frictional driving drum connected thereto 85 in any event when the potential switch is opened. This brake magnet circuit is further protected by the switch 217 and the limit switches 62' and 62. Furthermore, the switch 217 is held closed by the magnet 90 214, the current through which may be interrupted and the switch 217 therefore opened by movement of the car switch to central position, by opening the switch 208 at the controller board by the opening of the switch 25 connected with the safety apparatus mounted on the car, or by opening the manual safety switch SW in the car.

95 The insertion of the resistances in series with the brake magnet coil decreases the amount of current taken by the brake magnet, thereby lessening the consumption of current and decreasing heating. Furthermore, when the resistances are thus inserted 100 the brake apparatus will be let go or released by the magnet more quickly when the current from the mains thereto is interrupted. In order to apply the brake shoes gradually the motion of the magnet cores is 105 electrically retarded by shunting the brake coil with a high resistance. In my co-pending application, Serial No. 382,498, filed July 6, 1907, for an improvement in motor controlling apparatus, I have shown a high resistance permanently connected across the 110 brake magnet. In the present case, however I have shown a high resistance 224 only initially connected across the brake magnet coil 15' between the junctions 225 and 226 115 by means of the conductors 227 and 228 and the auxiliary switches 229 and 229'. These auxiliary switches are normally closed and in series with each other. When either portion of the reversing switch when considered as a whole is operated, the high resistance 224 is cut out: but when the reversing switch is permitted to open to effect a stopping of the motor, the high resistance 224 is again inserted in shunt with the 120 brake magnet coil or solenoid 15'. Upon the restoration of the reversing switch to initial position, the auxiliary switch 33 or 33' is opened to reinsert the resistance 64 in circuit with the brake magnet. Substantially at the same time that the reversing 125 130

switch is thus restored to normal, the current through the magnet 214 is cut off to effect the opening of the switch 217, thus cutting off the current supply from the mains to the brake magnet. Upon the interruption of the brake magnet circuit, the counter-electro-motive force of self-induction of the brake magnet will produce a current through the high resistance 224, the switches 229 and 229' being then both closed. This will tend to maintain the brake magnet energized so that the brake shoes will be applied gradually.

In order to effect a quick release of the brake mechanism when the brake magnet is energized, the plunger or core of the latter is preferably slotted longitudinally. It should also be noted that the less the current which holds the brake in released position, the quicker the magnet plunger can be let go when the current from the mains is cut off. The arrangement may be such, therefore, that upon stopping the motor the switch 33 or 33' is first opened to reinsert the resistance 64 in series with the resistance 123 so as to further cut down the current passing through the solenoid 15'. Then upon the opening of the switch 217 the resistance 224 is thrown across the solenoid 15' to effect a retardation of the motion of the brake shoes just as they are about to be applied to the brake pulley to positively stop the motor.

When the main line switch L is closed and current flows through the shunt field resistance SFR and the shunt field winding 28, the shunt field safety magnet will also receive current to close the switch 126 which controls the continuity of the circuit of the magnet 127 which holds the potential switch in closed position. The circuit controlled by the switch 126 may be traced from the junction 128 on main circuit 76, through conductor 129, switch 130, conductor 131, switch 126, conductor 132, individual switches 133, 134, conductor 135 and the resistance 136 therein, and thence through the electro-magnet 127, switch 137, conductor 138, individual switches 139 and 140, conductor 141, governor switch 142, conductor 143, blade 144 of the safety switch SW in the car, conductors 71, 73, to the contact 74. It will therefore be seen that this circuit is connected across the mains and includes the switches 130, 126, 133, 134, 137, 139, 140, 142, SW, and the electro-magnet 127. The opening of any one of these switches, therefore, will effect the deenergization of the potential switch magnet 127, and the consequent opening of the potential switch which will cause the slowing down and the stopping of the motor and the car. If the current through the shunt field should decrease to a predetermined value such that the operation of

speed would tend to become excessive, the shunt field safety magnet SFSM would not have sufficient strength to maintain the switch 126 closed. Upon the opening of the latter, the potential switch magnet 127 would be deenergized, with the result already stated. Furthermore, if the car should travel beyond its normal limits of travel, the cam 5 on the car would strike the roller on the lever operating the switch 34 on the up motion, or the roller of the lever for the switch 34' on the down motion, and therefore either the switch 133 or 134 would be opened, and consequently the circuit of the potential switch magnet interrupted. Should the operator in the car lose control of the hoisting apparatus, the opening of the safety switch SW in the car by the operator would also open the potential switch magnet circuit and cause the stopping of the car. It should be noted that the switch SW is arranged in the common return conductor of the electromagnets 127, 214 and the reversing switch magnets; also of the fast speed magnet referred to more fully hereinafter. The operation of the safety device mounted on the car to open the switch 25 automatically will also have the effect of interrupting the continuity of the return conductor, and thus quickly and automatically stop the elevator car. If during the normal running of the car the speed should exceed a predetermined limit, the governor device G will open the switch 142, thereby breaking the circuit of the potential switch magnet.

Should the potential applied to the mains a and b from the source of electric current supply exceed a predetermined limit, then the excess potential safety magnet EPSM would be sufficiently energized to open the switch 130 and thus break the circuit to the potential switch magnet. A circuit for the magnet EPSM may be traced from the junction 128, through the conductor 129, solenoid 146, resistance 147, and conductor 73 to the contact 74. The solenoid 146 is therefore connected across the mains. It should be noted that when one of the limit switches 34 or 34' is operated to open position, both terminals of the potential switch magnet 127 are entirely disconnected from other conductors so that there will be no possibility of maintaining the magnet 127 energized by the motor acting as a generator.

Should the main line current become interrupted while the motor is operating the latter might be converted into a generator and thence supply current to the potential switch magnet 127 to hold the potential switch P closed, permitting the motor to race. If the current supply is suddenly cut off the current through the shunt field safety magnet SFSM will be decreased at this time to permit the opening of the switch 126 so

that the circuit of the potential switch magnet may be interrupted, with the consequent effect of stopping the car. Should it happen, however, that the magnet SFSM is maintained energized by current generated from the motor and the switch 126 not opened before the car gains excessive speed, then the excess potential from the motor acting as a generator as the same speeds up will operate the magnet EPSM. The switch 130 will be opened by the latter to interrupt the potential magnet circuit and stop the motor. Should the acquired speed become excessive, then the governor will be operated first to effect a slowing down of the motor by cutting out some or all of the field resistance, and then interrupting the circuit of the potential switch magnet. The order of arrangement may be varied as desired by adjustments, but I prefer to have the magnet SFSM permit the switch 126 to open when the field strength decreases to a point where the motor speed becomes excessive when the latter acts as a motor, and, in the event that the motor acts as a generator and acquires excessive speed, that then the magnet EPSM will open the switch 130. Before the potential magnet circuit is interrupted by the opening of the switch 126, the arrangement should be such that the governor switch 186 will cause a slowing down of the motor, and thus in some instances prevent the necessity of the opening of the switch 126. In the event that neither the switch 126 nor 130 is opened, the switch 142 may be depended upon to be opened by the governor; or the switch 25 may be opened automatically by the elevator safety brake apparatus. These means for causing the opening of the potential switch are automatic and out of the hands of the operator, who of course is always able to stop the car by moving the switch lever 44 back to central position or by opening the safety switch SW.

Upon the closing of the reversing switch R' in the manner heretofore stated, a circuit will be immediately closed through the fast speed magnet FSM from the conductor 97, through the conductor 148, resistances 149 and 150, solenoid 151, conductor 152 to the junction 153, and thence through the safety switch SW and common conductor 71 to the contact 74. The fast speed magnet FSM will therefore be in a circuit connected directly across the mains and will operate the switch 154 to close the same and short-circuit the resistance SFR which is divided into two sections 155 and 156, but the switch 154 controls the entire resistance. It is therefore evident that when the reversing switch is operated the shunt field resistance SFR is immediately short-circuited, and therefore after the brake apparatus has been released so that the motor armature may turn, and

the shunt field resistance has been short-circuited, the shunt field will be at its maximum strength, all the series resistances will be in circuit with the motor armature and most of the by-pass resistance short-circuited. Hence when the lever 43 of the car switch S is moved in the direction of the up arrow and the contacts 51, 52 and 49 are electrically connected together, the motor may start at slow speed and will continue to operate at such speed until the lever receives additional actuation to cause the segment 48 to engage the contact 53. When this occurs a circuit will be closed from the positive main through the main line conductor 76, contacts 90, 88, conductors 157, 158, solenoid 159 of the speed controlling apparatus, resistance 160, conductor 161, limit switch 162, conductor 163, contact 53, car switch plate 67, contact 49, conductor 68, switch 208, conductors 69, 71 and 73 to the negative main. The switch 17 will then be closed to cut out the section 166 of the series resistance 31. At the same time the switch 21 will be opened to insert the section 165 in series with the section 117 in a circuit across the motor armature. The speed of the motor armature will therefore be increased a certain amount.

When the switch 17 is closed, the auxiliary contacts 167 and 168 are connected with each other so that when the controller lever 44 is moved to bring the plate 67 into engagement with the contact 54, the next solenoid 169 will receive current to close the switch 18 and open the switch 22. The remaining section of the minimum starting resistance 31 will therefore be short-circuited and an additional section of the by-pass resistance inserted. The closing of the switch 18 will permit the closure of the switch 19 when the controller plate 67 engages the contact 55; and the closure of the switch 19 will permit the solenoid 170 to receive current to close the switch 20 and open the switch 24 when the controller plate 67 engages the contact plate 56. Upon the closure of the switch 19 the solenoid 159 receives current independently of the car switch through the circuit from the positive main by way of the reversing switch R', conductors 157, 158, solenoid 159, resistance 160, conductor 171, contacts 172, 173, conductor 174, switches 208, 25 and SW, and conductors 71 and 73, and thence to the negative main. When the switch 20 is closed and the switch 24 opened, the by-pass resistance circuit is entirely interrupted.

With the switch 20 closed, the engagement of the controller plate 67 with the contact 57 closes the circuit of the accelerating magnet A across the armature. This circuit may be traced from the armature brush 103 to the conductor 102, switch 19, conductor 100, contacts 99, 98, conductors 148, 148', resistance 177, conductor 176, accelerating magnet A, 130

switch 20, conductor 178, section 179 of the starting resistance 30, conductors 111, 110, contacts 108, 109, solenoid 107, and conductors 106, 105 to the armature brush 104.

5 Associated with the accelerating magnet is a series of switches 180 which operate in a well known manner to gradually cut out the main starting resistance 30 as the speed of the motor increases. When the last switch 10 is closed an auxiliary switch 181 is also closed so as to short-circuit the fast speed magnet FSM and cause the latter to open the switch controlled thereby, and thus reinsert the shunt field resistance SFR and 15 still further increase the speed of the motor by weakening the shunt field. The short circuit around the solenoid 151 may be traced from the junction 182 through the conductor 183, switch 181, conductor 184, the 20 auxiliary contacts of the switch 20, conductor 185, contact 57, controller plate 67, contact 49, conductor 68, switches 208, 25, to the junction 153. The motor hoisting apparatus and car now operate at full speed.

25 If the speed should exceed a predetermined value, the governor G will first close the switch 186, and thus short-circuit the section 155 of the shunt field resistance through the conductors 187 and 40, thereby strengthening the field and slowing down the motor. Usually this is sufficient to prevent the car from running too fast. If, however, the car speed should continue to increase, the governor G will open the switch 142 to interrupt 30 the circuit of the potential switch magnet 127. The potential switch will then drop down, and the conductor 189 connected thereto will electrically connect the clips 190, 191. This will close a local circuit across the 35 motor armature through the conductors 102, 192, 118, 105, and a small section of the bypass resistance 32. This will cause an electro-dynamic braking action to slow down the motor while the mechanical brake is being 40 gradually applied, contacts 60 and 74 being entirely disconnected from any source of current supply when the potential switch P is open.

When the car switch S is moved back 45 toward its central position, the operations whereby the car is gradually brought to rest take place in substantially the reverse order of the steps already described as to the acceleration of the car from rest to full speed. The operation of the brake mechanism in stopping the car has already been pointed out.

The auxiliary load magnet ALM and the resistance 197 are connected in series in a 50 circuit across the motor armature between the junctions 198 and 199, through conductor 200. This magnet controls the switch 201 and which is connected by the conductor 202 to the solenoid 193 and, by the conductor 203 to the conductor 204 which leads

to the contact 55 of the car switch. If the car switch lever is left in full speed position as the car approaches either limit of travel, the automatic limit switches will operate to stop the car. When the car is thus stopping with average loads the switch 201 is kept open by the magnet ALM. If, however, the load is heavy and exceeds a predetermined value when the car is going up and is being stopped, or if the car is going down with a light load and is being stopped, the car would tend to stop before reaching the level of the floor landing. The armature would be slowed down to such a speed, however, that the potential across the latter would not be sufficient to cause the auxiliary load magnet ALM to hold the switch 201 open. Therefore, upon the closing of the latter, a circuit would be established from the positive main through the reversing switch R', conductor 158, solenoid 193, conductor 202, switch 201, conductors 203, 204, contact 55, plate 67, contact 49, conductor 68, switch 25, conductor 69, blade 70, conductors 71 and 73 to the negative main. When the switch 201 is closed and the solenoid 193 receives current, the switch 19 is closed or held closed so that the minimum starting resistance 31 will remain short-circuited and the opening of the switch 23 will cause the entire by-pass resistance to be inserted if the switches 22 and 23 are still open. The purpose of maintaining the current in the solenoid 193 or reestablishing current therein is to vary the slowing down resistance so that more current can be received by the motor armature than when an average load is being moved, so that the car will be carried automatically to its normal limits of travel, although the load in the car may exceed a predetermined value on the up motion or fall below a predetermined value on the down motion. It will be understood that the auxiliary load magnet is effective only when the car switch 55 is left on, and the car is being stopped automatically at either limit of travel. When the car is stopped by the operation of the car switch, the auxiliary load magnet is ineffective as the closing of the switch 201 cannot reestablish a circuit through the magnet 193, the circuit for said magnet being open at the car switch contact 55.

The foregoing description of the method of operation and system of control applies 60 to the arrangement used for passenger service particularly. For lifting heavy loads, such as safes, the auxiliary brake is brought into operative condition by moving the nuts 331, 331' and 330, 330' inwardly along 65 the rod 323 (Fig. 3). The switches 209, 210, 211 are closed and the switch 208 is opened by reversing the position of the switch H. The closing of the switch 209 short-circuits in this instance all of the 70

minimum starting resistance 31. The switch 210 short-circuits a portion of the starting resistance 30. As before described, the circuit through the armature at the time of starting the motor includes the resistances 30 and 31. The closing of the switches 209 and 210 therefore effects an increase in the initial current. The closure of the switch 211 short-circuits the shunt field resistance SFR through the conductors 333 and 334. A strong magnetic field is therefore maintained while the switch 211 is closed. The switch 211 also closes a circuit through the magnetic sheave 2, as follows,—

from the positive main through the conductors 36, 37, 335, winding of magnetic sheave 2, conductor 336, switch 211, conductors 333, 40 and 41 to the negative main. The sheave 2 is therefore magnetized to increase the adhesion between the magnetic cables and the peripheral face of the traction sheave. The switch 211 further controls the auxiliary brake circuit as will appear hereinafter. The opening of the switch 208 breaks the circuit leading from the contacts 49, 50 of the controller switch S to the negative main.

The operation is now as follows: Assuming the main line switch L and the potential switch P both to be closed, the push button switch 212 is operated to close a circuit through the magnet 214 as follows,—from the positive main through the potential switch, conductors 76, 213, magnet 214, resistance 215, conductor 337, switch 212, conductor 338, blade 70 of the safety switch SW, conductors 71 and 73 to the potential switch, and from the negative main. The magnet 214 thereupon closes the switches 216 and 217. The switch 217 closes a circuit as hereinbefore pointed out, including the resistance 64, switch 26, and main brake magnet coil 15'. The auxiliary brake magnet circuit is open at this time so that the movable parts of the elevator are securely held in stationary position even if the main brake should be released. The controller switch S is now operated, for example, to the left or in the direction marked 50 "Up", until the plate 67 engages the contacts 51 and 52 and closes the circuit from the positive main through the potential switch, conductors 76, 213, switch 216, conductor 220, limit switch 80, conductor 81, solenoid 83, conductor 84, limit switch 85, conductor 86, contact 52, plate 67, contact 51, conductors 66, 337, switch 212, conductor 338, switch SW, conductors 71, 73, and thence to the negative main. The solenoid 83 therefore receives current and operates the reversing switch R' which closes a circuit through the motor armature. This circuit is the same as heretofore traced, except the switches 209 and 210 being closed short-circuit the resistance 31 and a portion of the

resistance 30, leaving only a portion of the resistance 30 in series with the armature. The motor will therefore receive a heavy starting current, and, as the field is strongly magnetized at this time, a powerful starting torque will be obtained, as required for lifting a heavy load. The closing of the reversing switch R' causes the switch 33' to be also closed to short-circuit the resistance 64 and fully energize the main brake coil 15', and at the same time close a circuit through the auxiliary brake coil 327 as follows,—from the positive main through the potential switch P, conductor 76, blow-out coil 96, contacts 90, 88, conductors 97, 339, switch 33', conductors 340, 341, brake coil 327, conductors 342, 336, switch 211, conductors 333, 40, and thence to the negative main. Both brakes are therefore fully released substantially at the same time that the armature receives its initial current and the motor will operate at slow speed. If the car switch lever 44 is given a further movement to move the plate 48 successively into engagement with the contacts 53, 54, 55, 56 and 57, the circuits through the magnet coils 159, 169, 193, 170 and the accelerating magnet A will be successively closed and the magnets will operate as before described. These circuits, however, will in this instance be complete from the car switch S to the negative main by way of the contact plate 67, contact 51, conductors 66, 337, switch 212, conductor 338, switch SW, and conductors 71, 73. The bypass resistance 32 will be gradually introduced and its circuit finally interrupted as before. The circuit for the accelerating magnet A will also be closed and the remainder of the starting resistance 30 short-circuited if the speed of the motor becomes sufficient. The closing of the switch 181, however, to short-circuit the fast speed magnet FSM will have no effect on the shunt field circuit, as the short-circuit is maintained across the shunt field resistance by the switch 211. The maximum speed is therefore less than with passenger service.

To stop the car, the switch lever 44 is moved back to central position and the push button switch 212 then released. This effects the introduction of the resistance 30 into the armature circuit, the introduction and then short-circuiting of a greater portion of the bypass resistance in the bypass circuit, the operation of the reversing switch R' to open the armature circuit and cut off the current from the mains to the armature, and the opening of the brake magnet circuits to effect the application of both brakes. The operation of the reversing switch R' also closes a circuit across the motor brushes as follows,—from the brush 103 through conductors 102, 101, switch 209, conductor 100, contacts 95, 93, conductor 110; contacts 108, 109, coil 107, conductors 106, 105 to brush 130.

104; also from conductor 100 to contacts 99, 98, conductors 97, 157, contacts 92, 94, coil 107, and wires 194, 105 to brush 104. This circuit effects an electro-dynamic braking action and co-operates with the brakes to quickly bring the parts to rest without shock or jar. A quick stop may be effected at any time by releasing the push button 212, no matter where the car switch lever 44 happens to be. As all the circuits extending through the car switch include the push button switch 212, the opening of the latter will interrupt all of said circuits. The reversing switch R' will therefore be operated at once to open position, and consequently the current supply to the armature cut off and an electro-dynamic brake circuit established. The circuits of the brake magnets will also be opened and the brakes applied to quickly stop the motor. The use of the push button 212 secures a more perfect control of the mechanism as will be apparent when it is considered that when the switch 208 is open, it is necessary for the operator to maintain a continual pressure on the push button with his finger, or otherwise, while the car is in operation, and the safety circuit may be opened instantly by releasing the push button, which does not require the same time, thought, or presence of mind required to open the switch SW.

I am aware of the application of R. C. Smith, Serial No. 394,179, filed September 23, 1907, for a traction elevator control system, broadly claiming the principal features of the controlling circuits and connections; and in my co-pending application Serial No. 382,498, filed July 6, 1907, for an improvement in motor controlling apparatus, I have covered some improvements. In the present application I have shown the extra switches 208, 209, 210 and 211, the extra brake magnet 327, and the magnetic sheave 2, in addition to the circuits and connections shown in my co-pending application above referred to. In Fig. 1 the switches 208, 209, 210, 211 are shown combined in the multiple switch H. It should also be noted that the magnet 214, the switches controlled thereby, certain connections for controlling the main brake magnet, and the switch 212 have also been added. Fig. 1 shows also the extra brake magnet apparatus and in Fig. 3 this is shown in detail. Another addition is the mechanism shown in Fig. 1^a for securing a positive driving connection between the driving sheave 2 and the tension sheave 3.

Obviously those skilled in the art may make various changes in the details and arrangement of parts without departing from the spirit and scope of my invention as defined by the claims, and I desire therefore not to be limited to the precise construction herein disclosed.

Having thus fully disclosed my invention, what I wish to have protected by Letters Patent of the United States is:—

1. In motor-controlling apparatus, the combination with a brake magnet coil, of means for effecting changes in the circuit of said coil to cause the operation of the brake, a high resistance in shunt to said coil, and means for automatically effecting changes in the resistance circuit substantially at the time said first-named means is operated. 70

2. In motor-controlling apparatus, the combination with a brake, comprising a brake magnet winding, of means for effecting the operation of the brake, a high resistance in a shunt circuit to said winding, a switch in said shunt circuit, and means dependent on the operation of said first-named means for automatically operating said switch. 80

3. In motor-controlling apparatus, the combination with a brake magnet, of a reversing switch, a high resistance connected in parallel with the brake magnet coil, and a switch in the high resistance circuit and connected to the reversing switch for operation therewith. 90

4. In motor-controlling apparatus, the combination with a plurality of brake magnets, of means for controlling the operation of said magnets, and appliances for rendering one of said magnets normally inoperative. 95

5. The combination with an electric motor, of a resistance in circuit with the motor field windings, controlling mechanism comprising means for automatically short-circuiting the said resistance during a portion of the starting and stopping of the motor, and additional means for rendering said resistance ineffective during such operation and control of the motor. 100

6. The combination with an electric motor, of a resistance in circuit with the field windings, automatic means for short-circuiting said resistance, and a shunt circuit comprising a manually operable switch connected across the terminals of said resistance. 110

7. The combination with an electric motor, of an electro-magnetic brake, an electro-magnetic sheave and resistance in circuit with the field windings of the motor, and a single switch included in the circuits of the brake and sheave, and a circuit in parallel to said resistance. 120

8. The combination with an electric motor, of starting resistance in circuit with the motor armature, an accelerating magnet for varying said resistance, and a manual switch in a shunt around a part of said resistance. 125

9. The combination with an electric motor, of starting resistance, means governed by the speed of the motor for short-circuit. 130

ing said resistance during the acceleration of the motor, and a manual switch for closing a shunt around a part of said resistance independently of said means.

5. 10. The combination with an electric motor, of an accelerating magnet, sectional resistance controlled by said magnet, and means for maintaining a portion of said resistance short-circuited independently of the 10 accelerating magnet.

11. The combination of a motor, controlling apparatus comprising a controller switch operable in opposite directions to effect the starting and acceleration of the 15 motor in either direction to different speeds corresponding to the direction and extent of movement of said switch, conductors extending from said switch to the source of current supply, a circuit connected across 20 the conductors, a manual switch in said circuit, and a manual switch in circuit with one of said conductors and located between the controller switch and said circuit.

12. In an elevator, the combination with 25 a car, driving sheave, and hoisting ropes, of an electric motor connected to said driving sheave, motor-controlling apparatus, means for energizing said sheave, a main switch in the car connected to said motor-controlling 30 apparatus, and an auxiliary switch in the car coöperating with the main switch when said sheave is to be energized.

13. In an elevator, the combination with 35 a car, driving sheave, and hoisting cables, of an electric motor connected to said sheave, motor-controlling apparatus, a winding for energizing said sheave, a master switch connected to said motor-controlling apparatus, and auxiliary switches for varying the 40 motor-controlling apparatus and effecting the energization of said sheave to enable the elevator to lift comparatively heavy loads.

14. In an elevator, the combination with 45 a car, a magnetic driving sheave, and hoisting cables, of an electric motor connected to said sheave, motor-controlling apparatus comprising reversing switches and accelerating mechanism, a winding for said sheave, a master switch connected to said motor-controlling 50 apparatus, and auxiliary switches for varying said accelerating mechanism to

permit the motor to receive more current initially and to effect the energization of said sheave to enable the elevator to lift comparatively heavy loads.

55 15. In an elevator, the combination with a car, hoisting ropes, and driving mechanism, of an electric motor connected to said driving mechanism, motor-controlling apparatus, a main brake device applied and released whenever the motor starts and stops, an extra brake device normally held in released position, and connections to effect the substantially simultaneous operation of both 60 brake devices.

65 16. In an elevator, the combination with a car, hoisting cables, and a magnetic driving sheave, of an electric motor connected to said sheave, an electro-magnetic winding for energizing said sheave, main brake apparatus and means for applying and releasing the same during the normal operation of the elevator, extra brake apparatus normally held in off or released position, motor-controlling apparatus, a master switch connected 70 to said motor-controlling apparatus, and auxiliary switches for controlling said extra brake apparatus and said electro-magnetic winding of the driving sheave.

75 17. In an elevator, the combination with a car, hoisting ropes, and a driving sheave, of an electric motor directly connected to said sheave, main brake apparatus always operative to release or hold said driving sheave, auxiliary brake apparatus, appliances for 80 normally holding said auxiliary brake apparatus in released position, motor-controlling apparatus, a master switch connected to said motor-controlling apparatus, a winding for energizing said sheave, electric circuits 85 and connections for effecting the operation of both brakes together when said holding appliances are moved to inoperative position, and additional circuits and connections for effecting the energization of said sheave. 90

95 In testimony whereof, I have signed my name to this specification in the presence of two subscribing witnesses.
